UNITED STATES PATENT OFFICE

109,517

DESIGN FOR A COMBINATION LAMP AND GAME DEVICE

Arthur W. Krueger, Chicago, Ill., assignor to
Stephen Zidek, Riverside, Ill.

Application January 24, 1938, Serial No. 74,507

Term of patent 3½ years

To all whom it may concern:

Be it known that I, Arthur W. Krueger, a citizen of the United States, residing at Chicago, in the county of Cook and State of Illinois, have invented a new, original, and ornamental Design for a Combination Lamp and Game Device, of which the following is a specification, reference being had to the accompanying drawing, forming part thereof, in which:

Figure 1 is a front elevational view of a combination lamp and game device showing my new design; and

Figure 2 is a top plan view thereof.

The base of the combination lamp and game

device showing my new design has circular depressions on its top and four sides, provided in a number in accordance with the usual variations of a die, and except for such variations in the number of circular depressions, the rear elevational view corresponds to the front elevational view of Fig. 1, while the side elevational views can be understood from a consideration of both Figs. 1 and 2.

I claim:

The ornamental design for a combination lamp and game device as shown and described.

ARTHUR W. KRUEGER.
